Attorney.

UNITED STATES PATENT OFFICE.

JOHN J. RICHTER, OF THIEF RIVER FALLS, MINNESOTA.

PACKING-MACHINE.

1,283,562.

Specification of Letters Patent.

Patented Nov. 5, 1918.

Application filed October 28, 1916. Serial No. 128,325.

To all whom it may concern:

Be it known that I, JOHN J. RICHTER, a citizen of the United States, residing at Thief River Falls, in the county of Pennington and State of Minnesota, have invented a new and useful Improvement in Packing-Machines, of which the following is a specification.

This invention has for its primary object 10 the production of improved mechanism for packing cigars or other articles in compact bundles of any size desired within certain limits. A further object is to provide improved means for regulating the parts of 15 the mechanism so that it will accommodate any number of cigars or other articles which are to be tied in bundles. With these and other objects in view which will be apparent to those skilled in the art to which 20 my invention relates, my invention comprises the features of construction and combination of parts hereinafter described and set forth in the claims.

In the drawing forming part of this 25 specification, Figure 1 is a front elevation, and Fig. 2 is a section taken on the line X—X of Fig. 1.

In the drawing let A represent a suitable base on which a yoke B is mounted, said 30 yoke being hollow and containing part of the operating and adjusting mechanism of my invention. C, D and E are three sides of a rectangular packing space, the fourth being formed by the base. This space is for 35 the cigars or other articles which are to be packed. The side C is selectively positioned and held by a thumb bolt 2 passing through the lower portion of the plate and through a slot 3 in the base. The sides D and E are 40 movable inwardly to compress the articles into compact condition ready to be tied by a ribbon F or other fastening means. The sides D and E are respectively provided with plunger shafts 4 and 5 slidably mounted in the yoke in passages 6 and 7, said shafts and its adjusting parts being similar in construction. A description of one will therefore apply to both.

Each of the plungers has a central longitudinal bore 10 over the outer end of which is secured by threaded connection a cap 11. Closely fitting said bore and movable longitudinally therein is a knuckle 12 having an opening 13 and formed with a stem 14.

Surrounding this stem is a rotatable sleeve

15 having a threaded periphery 16 and an integral handle 17 by which it can be turned, said stem being headed at 18 over the end of the handle to hold the sleeve rotatably on the stem. 60

The sleeve 15 is in threaded engagement with the cap 11 so that by turning the handle the knuckle is adjusted by a micrometer or screw adjustment. Thus either of the sides D and E can be adjusted as to the ultimate inward position which it will assume by the inward throw of the operating mechanism to be hereinafter described. 65

Pivotedly mounted upon the pin 20 in the yoke is an operating handle 21, one arm 22 of which projects outwardly so that it can be manipulated by hand and the other arm projects inwardly and is secured by a link 24 to an arm 25 of a bell crank 26. This bell crank is pivoted at its angle in the yoke 75 and its other arm 27 plays freely in the opening 13 but engages the knuckle to reciprocate the side E when the handle 22 is swung up or down. Similar operating mechanism to that just described is provided 80 for the side D, a link 28 being similarly connected to a bell crank 29 but pivotally attached to that portion of the lever 21 on the handle side of the pivot thereof and the bell crank 29 having an arm 30 playing 85 freely in the opening 13 in the knuckle 12 which coöperates with the plunger 4. Thus both sides D and E are moved inwardly simultaneously to compress and form a bundle or moved outwardly simultaneously to release a bundle after it has been formed and tied. 90

When desired the stationary side C can be made to move inwardly and outwardly in synchronism with the movement of the sides 95 D and E within the spirit of my invention, in the same manner and by substantially duplication of the same construction above described.

In accordance with the patent statutes, I 100 have described the principles of operation of my invention, together with the apparatus which I now consider to represent the best embodiment thereof, but I desire to have it understood that the construction 105 shown is only illustrative, and that the invention can be carried out by other means and applied to uses other than those above set forth within the scope of the following claims. 110

Having described my invention, what I claim as new and desire to protect by Letters Patent is:

1. A packing machine for cigars and other articles, comprising, in combination, a base having an upward yoke, sides on said base forming a bundle compressing space, a plurality of said sides having hollow plunger shafts slidably supported in said yoke, a knuckle joint slidably mounted in each of said shafts, a screw adjustment between each of said knuckle joints and its adjacent shaft for regulating the inward thrust of said movable sides and means connected with said knuckle joint for moving said movable sides inwardly and outwardly.
2. A packing machine for cigars and other articles, comprising, in combination, a base

having an upward yoke, sides on said base forming with said base a bundle compressing space, a plurality of said sides having hollow plunger shafts slidably supported in said yoke, a knuckle joint slidably mounted in each of said shafts, a screw adjustment between each of said knuckle joints and its adjacent shaft for regulating the inward thrust of said movable sides, means connected with said knuckle joints for moving said movable sides inwardly and outwardly, one of said sides being selectively positioned in stationary position on said base, and means for securing said selectively positioned side in stationary position on said base.

In testimony whereof, I have signed my name to this specification.

JOHN J. RICHTER.
